UNITED STATES PATENT OFFICE.

RUSSELL W. BAKER, OF ANDERSON, INDIANA, ASSIGNOR TO DELCO-REMY CORPORATION, OF DAYTON, OHIO, A CORPORATION OF DELAWARE.

ARMATURE-ASSEMBLY APPARATUS.

Application filed April 12, 1927. Serial No. 183,079.

This invention relates to the manufacture of armatures for dynamo-electric machines and especially to apparatus for assembling a commutator upon an armature shaft in a certain relation to the armature windings.

It is an object of this invention to reduce the cost of performing the operation of assembling a commutator upon an armature shaft in a certain relation to the armature windings and of marking a certain bar of the commutator to which bar are related the subsequent operations of connecting the armature conductors with the commutator.

Further objects and advantages of the present invention will be apparent from the following description, reference being had to the accompanying drawings wherein a preferred embodiment of one form of the present invention is clearly shown.

20 In the drawings:

Fig. 1 is a front elevation of a machine embodying the present invention.

Fig. 2 is a side view partly in section.

Fig. 3 is a view similar to Fig. 2, showing the apparatus in its position after having forced a commutator upon an armature shaft, certain parts being shown in longitudinal section.

Fig. 4 is a sectional view on line 4-4 of Fig. 2.

Fig. 5 is a sectional view on line 5-5 of Fig. 2.

Fig. 6 is a sectional view on line 6-6 of Fig. 2.

Referring to the drawings, 20 designates a frame of the arbor press type and having a pedestal 21 which supports a movable rod 22 moved in both directions vertically by any suitable mechanism not shown, such as an air cylinder and piston. The rod 22 is provided with a groove 23 for receiving a key 24 which prevents rotation of the rod 22. The rod 22 is provided with a central bore 25 for receiving a spring 26 which urges downwardly a plunger 27 having a central bore for receiving the end of an armature shaft 60 when the plunger moves into the position shown in Fig. 3.

Rotation of the plunger 27 relative to the rod 22 is prevented by a screw 28 which projects into a groove 29 in the plunger 27. The screw 28 also limits the end-wise movement of the plunger 27 relative to the rod 22. The lower end of the plunger 27 provides a spring chuck comprising a plu-

rality of radially movable spring parts 30 provided by slitting longitudinally at 31 the thin walled cylindrical end of the plunger. This chuck is adapted to yieldingly support a commutator 32 having a central core 33 and a plurality of metal segments 34 insulatingly supported by it. The spring parts 30 press against the core 33 to hold the commutator core 33 in alignment with the rod 22. The lower end of the rod 22 is provided with an annular boss 35 adapted to engage the upper end of the commutator in order to strip the commutator from the plunger 27, as will be described.

The base 20 pivotally supports a shaft 40 carrying a tiltable table 41 comprising a hub portion 42 which swings in an opening in the base 20 between the bearings 43 and 44 for the shaft 40, and flanges 45 and 46 which carry buttons 47 adapted to rest upon plates 48 and 49 attached to the base. The base 20 supports a socket member 50 which is in alignment with the plunger 27 when the table 41 is in the position shown in Fig. 2. The socket member 50 has a central bore 51 for receiving an armature shaft 60 attached to an armature core 61 carrying windings 62. The windings 62 rest upon a suitable seat 52 provided by the socket member 50.

In order to locate the windings of the armature in a predetermined relation to the assembling apparatus, the table 41 supports a post 53 carrying a spring pressed plunger 54 having a thin blade 55 adapted to be received by a certain slot of the core 61. For example, the core slot which must receive the locating blade 55 may be the fourth one away from that slot from which emerge the ends 62^a of the last coil to be wound upon the core, coil 62^b as shown in Fig. 5.

I shall now describe the devices for locating the commutator 32 properly relative to the core 61, and for marking a certain one of its segments for identification as the starting point for the subsequent operations of connecting the armature conductor leads with the segments of the commutator, each segment having been slotted as shown at 34^a in Fig. 2. The rod 22 carries near its lower end a collar 70 which carries a pin 71 for pivotally supporting an arm 72 carrying a thin blade 73 adapted to enter the slot 34^a of any one of the commutator segments 34 to locate the commutator properly and to prevent it from turning. Springs 74, attached to pins

75 of the collar 70, and pins 76 of the arm 72, urge the arm 72 toward the commutator 32 and thus maintain the blade 73 within a segment slot 34^a. The arm 72 carries a pointed 5 pin 77 of hard metal bearing against that segment of the commutator which is vertically above a radial line passing through the axis of the shaft 60 and the central part of the upper end of the core slot into which the 10 blade 55 extends.

Before placing an assembly of armature shaft 60, core 61, and windings 62 upon the table 41, the table is tilted clockwise, as viewed in Fig. 2 from the position shown therein until a spring pressed plunger 90 guided by the base 20 enters a recess 91 in the hub 42 of the table. In this position of the table the socket member 50 is out of alignment with the rod 22 sufficiently to permit mounting an armature 15 assembly upon it with one end of the shaft 60 with the socket recess 51. The armature assembly is so mounted that the locating blade enters the proper core slot as shown in Fig. 5. Then the table with the assembly supported 20 thereby may be located as shown in Fig. 2, in which the shaft 60 is in vertical alignment with the rod 22. A commutator 32 is mounted upon the plunger chuck 30 with the locating blade 73 in one of its slots 34^a. The rod 25 22 is caused to move downwardly by any suitable power means in order to bring the end of the chuck 30 against a shoulder 60^c joining the commutator receiving portion 60^b of the shaft 60 with a portion 60^a of smaller diameter and 30 adapted to enter the central recess of the plunger 27. After the end of the chuck 30 strikes this shoulder 60^c, the rod 22 will continue to move downwardly to cause the boss 35 to engage the commutator 32 and to strip 40 it from the chuck 30 and to force it over the commutator receiving portion 60^b of the shaft 60.

By the time that the commutator 34 has been assembled upon the shaft 60, the pointed 45 pin 77 will have been forced into a segment 34 due to the engagement of a surface 78 of the arm 72 with a surface 79 of a bracket 80 which is adjustably secured to the pedestal 21. The bracket 80 is vertically slidable between 50 guides 81, and is secured by a washer 82 and screw 83 which passes through a slot 84 in the bracket 80 and is threaded into a tapped hole in the pedestal 21. Thus, a certain segment 34, which has been located in a predetermined 55 manner relative to a certain slot of the armature core, will be marked with a prick punch mark, which will identify that segment as being the one to which are related all of the subsequent operations of connecting the armature conductor leads to the commutator segments.

Following this commutator assembling and commutator marking operation the rod 22 is caused to return to the upper position to permit removal of the work from the socket mem-

ber which is preceded by tilting the work and table out of alignment with the rod 22.

This apparatus also shapes the conductors 62 which extend across the bottom of the core 61, referring to the location of the core in the 70 socket member 50. The member 50 provides a shoulder 100 for receiving a collar 101 attached to the shaft 60. This collar 101 may be an oil throwing spiral gear. The windings 62 will strike the seat 52 before the collar 101 75 strikes the shoulder 100. While the commutator 32 is being forced over the shaft portion 60^b, the windings 62 at the end of the core remote from the commutator are being compressed or shaped by the seat 52, and this 80 shaping continues until the collar 101 engages the seat 100. Therefore the conductors 62 will be compressed into a mass at this end of the core 61, which mass will be spaced a certain 85 distance from the collar 101. Hence a definite clearance will be provided between the windings 62 and the end frame of the dynamo.

After removing the screw 110, the socket member 50 may be removed and be placed by 90 one adapted to receive a core and shaft assembly having other dimensions.

While the form of embodiment of the present invention as herein disclosed, constitutes a preferred form, it is to be understood that other forms might be adapted, all coming 95 within the scope of the claims which follow.

What is claimed is as follows:

1. Apparatus for assembling an armature comprising a support for an assembly of armature shaft and an armature core carrying windings; a support for a commutator in alignment with the armature shaft; means for producing movement of one support relatively to the other in order to force the commutator over the armature shaft; and means responsive to said relative movement for marking one of the commutator bars.

2. Apparatus for assembling an armature comprising a support for an assembly of armature shaft and an armature core carrying windings; a support for a commutator in alignment with the armature shaft; means for producing movement of one support relatively to the other in order to force the commutator over the armature shaft; and means responsive to said relative movement for compacting the conductors adjacent one end of the armature core into a mass having a certain relation to the armature shaft.

3. Apparatus for assembling a commutator having a tubular hub upon a shaft having a commutator receiving portion, comprising in combination, means for supporting the shaft; means independent of the shaft for temporarily supporting the commutator 120 in alignment with the shaft and for locating it around the shaft and adjacent the commutator receiving portion thereof; means for removing the commutator from the temporary supporting means and for forcing it 125 into alignment with the shaft.

along the commutator receiving portion of the shaft; and means for marking a bar of the commutator placed upon said shaft.

4. Apparatus for assembling a commutator having a tubular hub upon a shaft having a commutator receiving portion and a portion of smaller diameter than the commutator receiving portion located between an end of the shaft and the commutator receiving portion, comprising in combination, a tube for receiving the commutator and adapted to receive the shaft portion of smaller diameter; means for supporting the armature shaft in alignment with the tube and in a certain angular relation therewith; means for producing relative movement between the tube and shaft so that the commutator will be located around the shaft and adjacent the commutator receiving portion thereof; means for transferring the commutator from the tube to the commutator receiving portion of the shaft; and means actuated during said relative movement for marking a bar of the commutator placed upon said shaft.

5. Apparatus for assembling a commutator having a tubular hub upon a shaft having a commutator receiving portion and a portion of smaller diameter than the commutator receiving portion located between an end of the shaft and the commutator receiving portion, comprising in combination, means for supporting the shaft and for maintaining the shaft in a certain angular position; means independent of the shaft for temporarily supporting the commutator in alignment with the shaft and in a certain angular relation to said shaft and for locating it around the shaft portion of smaller diameter; a tubular stripping member movable in alignment with the shaft and adapted to engage one end of the commutator and to remove it from the temporary holding means and to force the commutator along the commutator receiving portion of the shaft; and means actuated during the stripping of the commutator from the temporary holding means for marking a bar of the commutator placed upon said shaft.

6. Apparatus for assembling a commutator having a tubular hub upon a shaft having a commutator receiving portion and a portion of smaller diameter than the commutator receiving portion located between an end of the shaft and the commutator receiving portion, comprising in combination, a tube for temporarily holding the commutator and adapted to receive the shaft portion of smaller diameter; a stripper supporting and guiding the tube and adapted to engage an end of the commutator; means limiting relative movement between the tube and the stripper; means for supporting the shaft in alignment with the tube and in a certain angular relation to said tube; means for producing rela-

tive movement between the shaft and the tube and stripper whereby the commutator will be located around the shaft and adjacent the commutator receiving portion thereof, and then the stripper will cause the commutator to be transferred from the tube to the commutator receiving portion of the shaft; and means actuated during said relative movement for marking a bar of the commutator placed upon said shaft.

7. Apparatus for assembling a commutator having a tubular hub upon a shaft having a commutator receiving portion and a portion of smaller diameter than the commutator receiving portion located between an end of the shaft and the commutator receiving portion, comprising in combination, a tube for temporarily holding the commutator and adapted to receive the shaft portion of smaller diameter; a tubular stripper supporting and guiding said commutator supporting tube and adapted to engage an end of the commutator; a spring within the stripper for urging the tube outwardly from the stripper; means for limiting the outward movement of said tube relative to the stripper; means for supporting the shaft in alignment with the tube and in a certain angular relation to said tube; means for producing relative movement between the shaft and the tube and stripper whereby the commutator will be located around the shaft and adjacent the commutator receiving portion thereof, and then the stripper will cause the commutator to be transferred from the tube to the commutator receiving portion of the shaft; a member movably supported by the stripper and carrying an instrument for marking one of the commutator bars; and means for engaging said member during said relative movement for causing the instrument to mark a bar of the commutator placed upon said shaft.

8. Apparatus according to claim 7 in which the movable member carried by the stripper is provided with a part for entering a recess in the commutator in order to locate the commutator in a certain angular position.

9. Apparatus for assembling a commutator having a tubular hub upon a shaft having a commutator receiving portion, comprising in combination, means for supporting the shaft; means for temporarily supporting the commutator in alignment with the shaft; means for forcing the commutator upon the commutator receiving portion of the shaft; and means actuated during the forcing of the commutator upon the shaft for marking a bar of the commutator.

10. Apparatus for assembling a commutator having a tubular hub upon a shaft having a commutator receiving portion, comprising in combination, means for supporting the shaft; means for temporarily supporting the commutator in alignment with the shaft; means for producing relative axial movement

between the shaft and the commutator temporary supporting means in order to force the commutator over the commutator receiving portion of the shaft; a member carried by the commutator temporary supporting means and having an instrument for marking a bar of the commutator; and means engageable with said member for causing the instrument to mark the bar during said relative movement between the shaft and the means which temporarily supports the commutator.

11. Apparatus for assembling a commutator having a tubular hub upon a shaft having a commutator receiving portion, comprising in combination, means for supporting the shaft; a rod axially movable relative to the shaft and coaxial therewith; means carried by the rod for temporarily supporting the

commutator in alignment with the shaft; means for fixing the commutator in a certain angular position relative to the shaft; a lever pivotally supported by the rod and carrying an instrument engageable with the commutator for marking one of its bars; and a cam located in the path of movement of the lever when the rod is axially moved relative to the shaft in order to engage the lever and cause the instrument to mark a bar of the commutator.

12. Apparatus according to claim 11 in which the pivoted lever carries a part adapted to move into a recess provided by the commutator in order to prevent rotation thereof.

In testimony whereof I hereto affix my signature.

R. W. BAKER.
